UNITED STATES PATENT OFFICE.

CHARLS R. HAWKINS, OF CINCINNATI, OHIO.

ROTARY BALANCED VALVE.

SPECIFICATION forming part of Letters Patent No. 425,610, dated April 15, 1890.

Application filed September 9, 1889. Serial No. 323,380. (No model.)

To all whom it may concern:

Be it known that I, CHARLS R. HAWKINS, a citizen of the United States of America, and a resident of the city of Cincinnati, in the county of Hamilton and State of Ohio, have invented certain new and useful Improvements in Rotary Balanced Valves, of which the following is a specification.

The several features of my invention and the various advantages resulting from their use, conjointly or otherwise, will be apparent from the following description and claims.

In the accompanying drawings, making a part of this specification, Figure 1 is a vertical central section of the upper portion of a cylinder, steam-chest, and valve embodying my invention, the valve being in cross-section, the steam-chest and cylinder being in longitudinal section, the steam-ports for admitting steam to the cylinder being shown as closed by the valve. Fig. 2 is a vertical central section of a steam-cylinder, steam-chest, valve, and valve-box embodying my invention, the section as regards the cylinder and steam-chest being a longitudinal one and as regards the valve and valve-box being a transverse one. In this figure the valve is shown as admitting steam to one steam-inlet port of the cylinder and connecting the exhaust with the other or opposite steam-inlet port of the cylinder. Fig. 3 is a view in perspective of the valve proper of my rotary balanced valve. Fig. 4 is a view in perspective of a steam-chest receiving said valve and box. Fig. 5 is a view of the box containing the valve-chamber. Fig. 6 is a horizontal central section of the steam-chest and of the box containing the valve-chamber, that view of the section being shown which is apparent when the upper half of the steam-chest and valve-box is removed. Fig. 7 is an end view of the valve. Fig. 8 is an enlarged vertical central transverse section of my rotary valve. Fig. 9 is a view in perspective of the ring at end of the valve. Fig. 10 is a vertical central longitudinal section of one end of my improved valve, valve-chamber, and steam-chest. Fig. 11 is a view of one end of the steam-chest and the nut employed to lock the valve and valve-box in position. Fig. 12 is an elevation of the side of valve-chest and its exterior accompani-

ment, and showing a steam-cylinder in end elevation.

C indicates a cylinder of any desired description, having a piston C', operating a piston-rod C², reciprocating through the end of the cylinder, one end of the interior space of the cylinder being connected, as usual, with its appropriate steam-port C³, and the other end of the cylinder being connected, as usual, with its appropriate steam-port C⁴, the upper portion of the cylinder being further provided with the exhaust C⁵.

A indicates the steam-chest, preferably square in form, provided with the sides A' A' and ends A² A². This steam-chest is located, preferably, upon the top of the cylinder C. Of whatever shape the steam-chest may be, in any event it should be provided at each end with the recess or guideway A³ A³.

B indicates the valve-box. This valve-box contains valve-chamber B', cylindrical in form, for the reception of the rotary valve. For convenient adaptation to the various cylinders in use having a flat surface through which the ports C³, C⁴, and C⁵ open the bottom B³ of the valve-box is flat. In the lower portion of the valve-chamber B' are three ports B³ B⁴ B⁵, and these ports are continued downward through the bottom B³ of the valve-box. When the valve-box is placed in position, the port B³ will coincide with the port C³ to form one continuous passage from the valve-chamber B' to the interior of the cylinder C, and the port B⁵ will coincide with the port C⁴ and form one continuous passage to the other end of the interior of the cylinder C, and the port B⁴ will coincide with the exhaust-port C⁵ and form one continuous passage for the exhaust-steam to be conveyed away.

The steam-chest A surrounds the valve-box B, each end of the valve-box B being held in position within the steam-chest by suitable means, preferably by the guideways A³ A³, already described. In the latter case one end of the valve-box fits between the edges of the guideway A³ in one end of the steam-chest and the other end of the valve-box fits within the recess A³ in the other end of the steam-chest.

Steam is admitted to the valve-chamber B'

by passages, as B^6 B^7 , one of these passages being formed in and extending through the sides of the valve-box B from its exterior to the valve-chamber B' , passage B^6 being at one side of the valve-box and passage B' on the other.

Where the valve and its ports are placed near to and over the cylinder, substantially as shown in Figs. 1 and 2, the steam-chest will then rest upon a proper facing located at the top of the cylinder C . The steam-chest is provided with a suitable top A^4 . The joints between the top and the walls of the steam-chest are made steam-tight, and so are the joints between the steam-chest and the face or bottom upon which it rests. The bottom of the valve-box B^2 and the face upon which it rests are ground smooth and together form a steam-tight joint, the pressure of steam in the steam-chest pressing down upon the valve-box to form, in conjunction with the face on which it rests, a steam-tight joint.

The central supporting portion of the valve consists of a cylinder D , provided with three large longitudinal recesses D' , D^2 , and D^3 . In the longitudinal wall R' , lying between recess D^3 and recess D^2 , is a similar longitudinal recess R^2 , and in the longitudinal wall R' , which separates recess D^2 from recess D' , are two similar parallel longitudinal recesses R^2 . Each of these recesses receives a rib R^8 , which may be properly termed a "packing-strip." This rib R^8 consists of a proper material for use as a packing—namely, cast-steel or equivalent material. The outer surface of each rib R^8 extends beyond the general peripheral surface of the central supporting portion D of the valve.

The recesses R^2 and the packing-ribs R^8 extend the entire length of the central supporting portion D of the valve, and each end of each rib R^8 is provided at its inner edge with an extension R^4 . Thus at one end of the valve there are four extensions R^4 , and at the other end of the valve there are four extensions R^4 , each set of four extensions R^4 extending out beyond the ends of the central supporting portion D of the valve. At each end of the main or central supporting portion D of the valve a lug D^4 , fixed thereto, is present, for a purpose shortly to be specified. Around the extensions R^4 at one end of the cylinder is placed a ring R^5 , and at the other end of the cylinder a similar ring R^5 embraces the four ends R^4 of the ribs R^8 . These rings prevent longitudinal displacement of the packing-ribs R^8 . Within the four extensions R^4 of one end of the cylinder an elastic ring R^6 is present, which exerts an elastic pressure outwardly upon the extensions R^4 , and consequently upon the packing-ribs R^8 . At the other end of the cylinder a similar ring R^6 , within the ends of the extensions R^4 , exerts an elastic pressure in the direction outward from the axis or stem of the valve, and thereby coacts with the rings R^5 at the other

end of the valve in pressing outwardly the ribs R^5 .

The valve is located within the valve-chamber B' of the box B , and when thus placed 70 each of the packing-ribs R^8 , through the agency of the elastic ring R^6 or its equivalent device, is pressed outward against the interior surface of the valve-chamber B' , and thus forms a tight packing-joint, which prevents the passage of steam from any one of the recesses D' D^2 D^3 to any of the other said recesses. 75

At the end of the valve is a solid ring R^7 , whose inner side fits against the outer edge 80 of the elastic ring R^6 and the outer edge of the exterior ring R^5 . The exterior ring R^5 , elastic ring R^6 , and end ring R^7 are prevented from rotating by means of the aforementioned lug D^4 in the following manner: The 85 ring R^5 has a slot through its periphery, and when placed in position upon the valve the lug D^4 passes through said slot S . The elastic ring R^6 also has a slot S' , and when in position upon the valve the lug D^4 passes 90 through this slot. On the inner side of the elastic ring R^7 and bordering upon the edge of its central opening R^8 , through which latter passes the stem of the valve, is fixed a ring R^9 , having a slot S^2 in its periphery. 95 When the ring R^7 is in position, the ring R^9 surrounds the valve-stem E inside of the elastic ring R^6 , and the lug D^4 passes through the slot S^2 . Thus the ring R^7 and the elastic ring R^6 and the exterior ring R^5 will be prevented from rotating around the valve-stem 100 E . All friction occasioned by the rotation of these rings is thereby obviated.

At the other end of the valve is found a similar set of rings, as R^5 , R^6 , and R^7 , and these rings are applied to the adjacent end of the valve in the same manner as the rings heretofore described are attached to their end of the valve, and the adjacent stud D^4 prevents the revolution of the said second set 105 of rings R^5 , R^6 , and R^7 in the same manner as the stud D^4 at the first-named end of the cylinder prevents the rotation of the first-named set of rings R^5 , R^6 , and R^7 .

In each end of the steam-chest is an opening 115 A^4 . The diameter of each of these openings A^4 is substantially that of the diameter of the valve-chamber B' in valve-box B . When the valve-box B is placed in position in the steam-chest, the respective ends of said valve-box fit 120 into the respective guideways A^3 A^3 of the chest, as shown in Fig. 6, and the bottom of the valve-box will rest upon the face C^6 , on which are the mouths of the steam-ports communicating with the cylinder C and the exhaust 125 port communicating with the exhaust-pipe C^5 , the port-passage B^3 of the valve-box meeting the port-passage C^3 , leading to the cylinder and forming one continuous passage, and the port-passage B^4 of the valve-box meeting the port-passage C^4 of the cylinder and forming 130 one continuous passage therewith, and ex-

haust-port passage B⁵ meeting the exhaust C⁵ and forming one continuous passage therewith.

The rotary valve is passed through one of the openings A⁴ in one end of the steam-chest A into the valve-chamber B' of the valve-box. It is secured in position by the following means, namely: A discal head A⁶ is provided with an outlying flange A⁷, and another portion of its periphery is provided with a screw-thread A⁸, and the inner portion of its periphery A¹² is smooth. This discal head A⁶ is provided on its inner side with a recess or opening A⁹, into which the shorter end of the valve-stem E fits. The head A⁶ is screwed into the opening A⁴, and the shorter end of the valve-stem E enters the recess A⁹ of the discal head A⁶. This recess A⁹ thus forms a bearing in which the short end of the valve-stem rotates. The smooth portion of the periphery A¹² of this discal head A⁶ enters within the end of the valve-chamber and fits closely therein and prevents the valve-box from vertical elevation. For convenience in screwing the discal head in and out its flanged end A⁷ is provided with notches A¹⁰ for affording to a suitable wrench a means of engaging with said head and turning the latter. At the other end of the valve-stem E is a discal head A⁶, provided with a similar flange A⁷, having notches A¹⁰ and provided with a peripheral screw-thread A⁸, for a purpose hereinbefore mentioned in connection with the aforementioned discal head A⁶. The smooth peripheral inner end of this last-named discal head A⁶ fits within the adjacent end of the valve-chamber B' and prevents vertical elevation of the valve-box. The opening or bearing A⁹ of this last-mentioned discal head A⁶ extends through the discal head. This head is screwed into the other opening A⁴ of the steam-chest, and preferably extends beyond the latter, substantially as shown in Fig. 12. The recess A⁹ of this discal head forms a bearing in which this end of the valve-stem may rotate. To the outer end of this end of the valve-stem is connected an arm F of suitable description. This arm F is suitably connected with mechanism whereby the valve is oscillated.

The operation of my valve is in general as follows: Steam being admitted into the steam-chest A through the inlet-steam opening A⁵, presses the valve-box B securely down upon the face C⁶ and prevents any steam from entering between the lower face of the valve-box and the face C⁶, containing the ports C³, C⁴, and C⁵. The steam through the cylinder enters into recess D' of the valve through opening A⁶ of the valve-box, and steam enters recess D¹² of the valve through openings B⁷ of the valve-box, and the ports B³ and D³ being closed by the ribs R³ R⁸, all admission of steam to the cylinder is for the time cut off. As the steam has free access into the valve-chamber through the openings B⁶ B⁷ of the valve-box, the steam does not unduly press down the

valve-box, but exerts within the valve-chamber an upward as well as a downward pressure, thereby contributing to balance the valve-box and valve. The valve being rotated to the position shown in Fig. 2, the steam admitted from the steam-chest through opening B⁶ into recess D' of the valve passes through the continuous ports B³ C³ into the cylinder behind the piston C' and drives the latter forward to the other end of the cylinder in the usual manner. At the same time the recess D³ of the valve connects the exhaust-port B⁵ with the continuous port B⁴ C⁴ and allows the gases in the other end of the cylinder in front of the piston to escape out of the exhaust. When the piston has arrived at that end of the cylinder at which the port C⁴ enters, the valve is caused to assume a position exactly the reverse of the one shown in Fig. 2. Then the recess D³ of the valve connects the continuous port B⁴ C⁴ with the inlet-opening B⁷ in the valve-box, and steam from the steam-chest passes through the opening B⁷, recess D², and port B⁴ C⁴ into the cylinder and impels the piston back through the cylinder. At the same time the exhaust B⁵ is connected with the ports B³ C³ and allows the gases in front of the cylinder to escape out of the exhaust. Thus by this oscillation of the valve the piston is reciprocated back and forth, and this reciprocation of the piston will be continued so long as the valve is oscillated.

While the various features of my invention are preferably employed together, one or more of the said features may be employed without the remainder, and in so far as applicable one or more of said features may be applied in connection with valve-boxes other than the combined device herein specifically set forth.

What I claim as new and of my invention, and desire to secure by Letters Patent, is—

1. A rotary balanced valve provided with recesses D' D² D³, longitudinal recesses R², and ribs R³, fitted within the said recesses and elastically pressed against the inner wall of the cylindrical valve-chamber, substantially as and for the purposes specified.

2. A rotary balanced valve having recesses D' D² D³ and longitudinal recesses R², each containing a rib R³, provided at each end with extensions R⁴ and ring R⁵, embracing said extensions, and the elastic ring R⁶, lying within said extensions and pressing outwardly against the said extensions R⁴, substantially as and for the purposes specified.

3. A rotary balanced valve having recesses D' D² D³ and longitudinal recesses R², each containing a rib R³, provided at each end with extensions R⁴ and ring R⁵, embracing said extensions, the elastic ring R⁶, lying within said extensions and pressing outwardly against the said extensions R⁴, and lug D⁴, passing through the slots in said rings R⁵ R⁶, substantially as and for the purposes specified.

4. A rotary balanced valve having recesses

D' D² D³ and longitudinal recesses R², each containing a rib R³, provided at each end with extensions R⁴ and ring R⁵, embracing said extensions, the elastic ring R⁶, lying within said extensions and pressing outwardly against the said extensions R⁴, and lug D⁴, passing through the slots in said rings R⁵ R⁶ and the discal ring R⁷, provided with ring R⁹, having slot S², said ring R⁹ fitting within the elastic ring R⁶ and lug D⁴ passing through slot S² of the ring R⁹, substantially as and for the purposes specified.

5. The steam-chest provided with guideways A³ A³, consisting of central recesses in the ends of the chest, rotary valve, and valve-box surrounding said valve and having its respective ends respectively located in the adjacent recesses of the said valve-chest, a space being left between each side of the 15 valve-box and the adjacent side of the steam-chest, substantially as and for the purposes specified.

6. The steam-chest A, provided with guideways A³ A³ and valve-box B, containing rotary valve, the respective ends of the valve-box B being provided with side openings B⁶ B⁷ and the lower openings B³ B⁴, the valve-chamber B' containing a rotary valve working therein, substantially as and for the purposes specified.

7. The steam-chest A, provided with guideways A³ A³, valve-box B, lying within said steam-chest and fitting into said guideways A³ A³, the valve-box being provided with side openings B⁶ B⁷ and lower openings B³ B⁵ B⁴, the valve being provided with recessed divisions D' D² D³ and with valve-stem E, the steam-chest being provided at each end with screw-threaded openings A⁴, and discal head A⁶, 35 screwed into said openings, each discal head being provided with opening A⁹, forming a bearing for its adjacent portion of the valve-stem, one end of the valve-stem projecting through and beyond one of the discal heads 40 and provided with arm or lever F, substantially as and for the purposes specified.

8. The steam-chest A and valve-box provided with valve-chamber B', the steam-chest

A being provided with openings A⁴, receiving the discal heads A⁶, having bearings A⁹ for 50 the valve-stem, the valve being located in the valve-chamber B, the ends of the discal heads respectively entering the adjacent ends of the valve-chamber, substantially as and for the purposes specified.

9. The discal heads A⁶, provided with notches A¹⁰, screw peripheral portion A¹², steam-chest A, provided with openings A⁴, valve-box B, having valve-chamber B', valve-stem E, rotating in openings A⁹ in the respective discal heads A⁶, the smooth peripheral portion A¹² of the discal heads extending into the adjacent end of the valve-chamber, and the screw-thread of the disk engaging a screw-thread upon the adjacent opening A⁴ in the 60 steam-chest, substantially as and for the purposes specified.

10. The steam-chest A, provided with end guideways A³ A³, screw-threaded openings A⁴ A⁴, located in the ends of the said steam-chest, 70 valve-box B, having valve-chamber B', openings B⁶ B⁷ in the sides of the valve-box and connecting the interior space of the steam-chest with the valve-chamber B', and lower openings B⁴ B⁸, connecting the valve-chamber with the corresponding ports C³ C⁴ of the cylinder, and lower opening B⁵ of the valve-box connecting the valve-chamber with the exhaust C⁵, and rotary valve B, having recesses D' D² D³ and intervening longitudinal 75 recesses R⁶, each recess having thereon a longitudinal rib R⁷, provided at each end with an extension R⁴ and slotted rings R⁵ A⁶, and ring R⁷, having slotted ring R⁹ and valve-stem E, and lugs D⁴ D⁴, each lug lying within 80 the slots of the adjacent rings aforementioned, and the discal heads A⁶, having openings A⁹, receiving the valve-stem, said heads A⁶ being provided with peripheral screw-thread A⁸ and smooth portion A¹² at each end 85 of the valve-chamber, substantially as and for the purposes specified.
